UNITED STATES PATENT OFFICE.

ANDREW HARMON WALLACE, OF ST. CATHERINES, ONTARIO, CANADA.

PHOTOGRAPHIC-PRINTING DEVICE.

1,159,441.

Specification of Letters Patent.

Patented Nov. 9, 1915.

Application filed June 27, 1913. Serial No. 776,129.

To all whom it may concern:

Be it known that I, ANDREW HARMON WALLACE, of the city of St. Catherines, in the county of Lincoln, in the Province of Ontario, Canada, have invented certain new and useful Improvements in Photographic Printing Devices, of which the following is the specification.

My invention relates to improvements in photographic printing devices and the object of the invention is to devise a simple adjustable device for printing a white border around a photograph of any size and which may also be adjusted to print any width of border desired and it consists essentially of a main frame having a window opening and window therein, two frame members extending at right angles one to the other along two adjacent sides of the window, resilient means for holding the plates flat against the surface of the frame, means for raising one or both of such members to free the underlying film, co-acting adjustable frame members extending along the opposite sides 25 of the window, a covering shutter and adjustable stops supported by one of the members of the right angular frame portion as hereinafter more particularly explained by the following specification.

Figure 1, is a general perspective view of my device, showing the covering shutter raised. Fig. 2, is a similar view of Fig. 1, showing the position the parts assume when freeing the film. Fig. 3, is a cross section 35 through Fig. 1, showing the shutter in its closed position. Fig. 4, is a sectional detail of the means for connecting the adjustable frame members of the frame.

In the drawings like letters of reference 40 indicate corresponding parts in each figure.

A is a printing frame provided with a window orifice A' and a window glass A² secured within the orifice.

B is the usual shutter formed in two parts 45 B' and B² hinged together and provided with any suitable securing means.

C is a bracket secured to one side of the frame and to which is connected a hinged plate C'.

C² is a frame member extending along one 50 side of the window opening A' and suitably secured to the hinge plate C'.

C³ is a hinge spring having a tendency to hold down the frame member in the hori-

zontal position shown in Fig. 1. The frame member C² is provided with a series of graduations C⁴.

D is a frame member extending at right angles to the frame member C². The frame member D is also provided with a suitable graduation D'.

D² are spring lips extending down from the member D and secured by suitable screws or other means D³ to the side of the frame A, the normal tendency of the spring lips 65 D² being to throw the plate up into the angular position shown in Fig. 2. It will also be understood that the adjacent ends of the members C² and D overlap.

E are diagonally disposed slots formed 70 in the member C².

E' is a right angular gage plate provided with pins E² extending down into the slots E so as to be in frictional engagement with the sides thereof.

E³ and E⁴ are two pair of cross slots 75 formed in the member C², and E⁵ and E⁶ are supplemental gage plates provided with pins E⁷ extending into the slots E³ and E⁴ so as to be in frictional engagement with 80 the sides thereof.

H is a raising lever pivoted at H' and provided with a pin H² extending inwardly into the notch A⁴ and extending beneath the plate C'.

I and I' are co-acting adjustable frame members slidably connected to the rods I³ and I⁴ by clips I⁵ and I⁶, such clips comprising a sleeve I⁷ to which the adjustable members are directly connected and spring 90 latches I⁸ carried by the sleeve designed to engage with the series of notches I⁹ formed in the rods I³ and I⁴. In this present application I do not lay any particular claims to the construction of this form of clip and 95 the adjustable member connected thereto as it forms a portion of the subject matter of a previously filed application.

When it is desired to print a picture the film 1 is placed on the glass A² and on top 100 of the adjustable members I and I' see dotted lines in Fig. 1, with two of its edges extending at right angles to each other beneath the frame members C² and D, such frame members being in the position shown 105 in Fig. 2. The lever H is then thrown down into the position shown in Fig. 1, releasing the frame member C² which is carried down

against the face of the frame by means of the hinged spring C³ and on top of the frame member D extending at right angles thereto. The spring C³ is slightly stronger than the 5 resiliency of the lips D², and, therefore, when the frame member C² is released it forces the frame member D into the horizontal position shown in Fig. 1 and on top of the edge of the film. The stop plates E', 10 E⁵ and E⁶ are then adjusted to print the required width of white border on the paper. The paper 2 is then laid upon the top of the film with its edge against the inner edge of the plate E', E⁵ and E⁶. The adjustable 15 frame members I and I' are also adjusted beneath the film and paper to print the corresponding width of white border along the corresponding sides of the paper. The shutter B is then thrown over into the position 20 shown in Fig. 3 covering the paper and is secured in any usual manner.

From this description it will be seen that I have devised a very simple form of printing frame for printing a white border around 25 a photograph of any size and by which the width of the border may be varied according to the desire of the operator.

What I claim as my invention is.

1. In a photographic printing device, the 30 combination with the frame having an opening, of a frame portion comprising two members extending at right angles one to the other and extending along two adjacent sides of the opening, and overlapping at 35 their adjacent ends, resilient means tending to raise the underlying portions, and resilient means for forcing the overlying portion down against the frame, means for raising such overlying portion, and co-acting adjustable frame members extending along the 40 opposite sides of the opening, as and for the purpose specified.

2. In a photographic printing device, the 45 combination with the frame having an opening, of a frame portion comprising two frame members extending at right angles one to the other, and provided with suitably arranged graduations, means for holding the frame portion against the film supported by 50 the frame and co-acting adjustable frame members extending along the opposite sides of the opening, and a covering shutter extending over the opening, as and for the purpose specified.

3. In a photographic printing device, the 55 combination with the frame having an opening, of a frame portion comprising two frame members extending at right angles one to the other, stop plates carried by one 60 of the frame members against which the edge of the paper overlying the film is designed to extend and rest, means for holding the frame portions against the film supported by the frame and co-acting adjustable 65 frame members extending along the opposite

sides of the opening, and a covering shutter extending over the opening, as and for the purpose specified.

4. In a photographic printing device, the combination with the frame having an opening, of a frame portion comprising two frame members extending at right angles one to the other, adjustable stop plates carried by one of the frame members against which the edge of the paper overlying the film is designed to extend and rest, means for holding the frame portion against the negative supported by the frame, co-acting adjustable frame members extending along the opposite sides of the opening and a 70 covering shutter extending over the opening, 75 as and for the purpose specified.

5. In a photographic printing device, the combination with the frame having an opening, of a frame portion comprising two frame members extending at right angles one to the other, one of such members being provided with cross slots, adjustable plates provided with pins extending down into such slots and in frictional engagement with 80 the sides of the slots, means for holding the frame portion against the film supported by the frame, co-acting adjustable frame members extending along the opposite sides of the opening, and a covering shutter extending 85 over the opening, as and for the purpose specified.

6. In a photographic printing device, the combination with the frame having an opening, of a frame member comprising two portions, one portion hinged at the side of the window opening and provided with resilient means for forcing such member into a horizontal position, and a portion underlying the aforesaid portion at its end, as and for the 90 purpose specified.

7. In a photographic printing device, the combination with the frame having an opening, of a frame member comprising two portions, one portion hinged at the side of the window opening and provided with resilient means for forcing such member into a horizontal position, and a portion underlying the aforesaid portion at its end, and provided with resilient means tending to raise 100 such portion when freed, as and for the purpose specified.

8. In a photographic printing device, the combination with the frame having an opening, of a frame portion comprising two 105 separate coöperating members extending at right angles one to the other along two sides of the opening, and stop pins carried by one of the members and adjustable transversely thereof, as and for the purpose specified.

9. In a photographic printing device, the combination with the frame having an opening, of a frame portion comprising two separate coöperating members extending at right angles one to the other along two sides of the 115

opening, and stop pins carried by one of the members and adjustable transversely thereof, and a transverse series of graduations on such member by which the stop pins are set, 5 as and for the purpose specified.

10. In a photographic printing device, the combination with a frame having an opening opposite which the negative and overlying paper are designed to be supported, of a frame member formed of thin sheet material overhanging the edges of the frame opening and comprising two portions, one of said portions extending at its edge between the marginal edges of the negative 15 and the paper, and means for raising such portion, as and for the purpose specified.

11. In a photographic printing device, the combination with a frame having an opening opposite which the negative and overlying paper are designed to be supported, of a frame member formed of thin sheet material overhanging the edges of the frame opening and comprising two portions, one of said portions extending at its edge between the marginal edges of the negative 20 and the paper, and means for raising each portion, as and for the purpose specified.

12. In a photographic printing device, the combination with a frame having an opening opposite which the negative and overlying paper are designed to be supported, of a frame portion formed of thin sheet material comprising two separate co-operating members extending at right angles one to 30 the other along two adjacent sides of the opening and at their edges between the film and the paper, one member being raisable, as and for the purpose specified.

13. In a photographic printing device, the combination with a frame having an opening opposite which the negative and overlying paper are designed to be supported, of a frame portion comprising two separate co-operating raisable members extending at 40 right angles one to the other along two adjacent sides of the opening and at their edges between the marginal edge of the film and the paper, as and for the purpose specified.

14. In a photographic printing device, the combination with the frame having an opening, of a frame portion comprising two separate co-operating members extending at 50 right angles one to the other along two ad-

jacent sides of the opening, one member raisable to permit placing the edge of the 55 negative beneath it and having a spring tendency downward to hold the negative as and for the purpose specified.

15. In a photographic printing device, the combination with the frame having an opening, of a masking portion comprising two members stationary as to lateral movement extending at right angles one to the other along two adjacent sides of the opening one member raisable to permit placing the negative 60 beneath it, co-acting adjustable masking members extending along the opposite sides of the opening and a covering shutter extending over the opening as and for the purpose specified. 70

16. A photographic printing frame, comprising a frame member provided with a transparent panel, a cover adapted to extend over the upper surface of the frame member, and clamping means pivotally mounted 75 on said frame member adjacent to said panel, and adapted to be revolved to a position between said transparent panel and cover, to release and engage a negative independently of said cover. 80

17. A photographic printing frame, comprising a frame member provided with a transparent panel, a clamp comprising a strip of metal hinged to said frame member, and adapted to be revolved to engage 85 and release a negative, tension means acting on said clamp, and a cover hinged to the frame member and adapted to extend over said panel in overlapping engagement with said clamp. 90

18. A photographic printing frame, comprising a frame member provided with a transparent panel, a clamp comprising a strip of metal hinged at its outer margin to said frame member, and adapted to be revolved 95 to engage and release a negative, tension means acting on said clamp, adjacent to its outer margin, and a cover hinged to the frame member and adapted to extend over said panel in overlapping engagement with 100 said clamp.
